UNITED STATES PATENT OFFICE.

THEODORE A. WILLARD, OF CLEVELAND, OHIO.

DESIGN FOR A FILAMENT FOR ELECTRIC LAMPS.

41,873.

Specification for Design. Patented Oct. 31, 1911.

Application filed April 1, 1909. Serial No. 487,362. Term of patent 7 years.

To all whom it may concern:

Be it known that I, THEODORE A. WILLARD, a citizen of the United States, residing in Cleveland, in the county of Cuyahoga and State of Ohio, have invented a new, original, and ornamental Design for Filaments for Electric Lamps, of which the following is a specification, reference being had to the accompanying drawing, forming a part thereof.

Figures 1, 2 and 3 are elevations of the filament taken from different sides, Figs. 2

and 3 being taken from points at right angles to each other, and Fig. 1 being a three-quarter view considering Fig. 3 as presenting a front elevation.

I claim:

The ornamental design for a filament for electric lamps, as shown.

THEODORE A. WILLARD.
